UNITED STATES PATENT OFFICE.

HENRY B. JONES, OF PHILADELPHIA, PENNSYLVANIA.

INKSTAND.

SPECIFICATION forming part of Letters Patent No. 283,348, dated August 14, 1883.

Application filed March 23, 1883. (No model.)

To all whom it may concern:

Be it known that I, HENRY B. JONES, a citizen of the United States, and a resident of Philadelphia, Pennsylvania, have invented 5 certain Improvements in Inkstands, of which the following is a specification.

My invention relates to certain improvements in that class of inkstands in which the hinged lid of the ink-bottle is connected to a 10 pivoted pen-rack, so that the said lid will be closed when the pen-holder is laid upon the rack, and will be permitted to open when the weight of the pen-holder is removed from the rack.

15 My invention consists, first, of an improvement in the construction of the pivoted pen-rack with side frames and weights adjustable on the arms of said side frames; and, second, of an improved hinge-connection between the 20 ink-bottle and lid, which may be applied to an ordinary inkstand, as more fully described hereinafter.

In the accompanying drawings, Figure 1 is a perspective view of an inkstand with my improvements; Fig. 2, a longitudinal section of the same, partly in elevation; Fig. 3, a side view of the upper end of the ink-bottle, and of the lid and its hinge-connection detached from the bottle; Fig. 4, a sectional plan on the line 30 1 2, Fig. 2; and Fig. 5, an enlarged perspective view of the hinge-joint for the lid of the bottle. Figs. 3, 4, and 5 are on a larger scale than Figs. 1 and 2.

The frame of the stand comprises the base 35 A and opposite side frames, B B, carrying the rod a, on which is hung the pen-rack D, the latter comprising the opposite side frames, b b, and the connecting-bars d.

The ink-bottle F is adapted to a seat, e, on 40 the base A, and as it is necessary that said ink-bottle should always preserve its proper relation vertically to the rack D, I lock the bottle to the seat e by means of segmental ribs f on the bottle, these ribs being adapted 45 to grooved lugs g on the seat e, so that by applying the bottle to the seat and then turning the same part way around, in order to cause the engagement of the ribs and lugs, the bottle will be firmly retained.

The lid G is hinged to a collar on the neck 50 of the bottle, as described hereinafter, and said lid is connected by a rod, h, to one of the cross-bars d of the rack D. Said rack D is so weighted in the rear of its pivot-rod that when the pen-holder is removed from the 55 rack, as shown in Figs. 1 and 2, the lid G will be elevated and the mouth of the bottle F opened; but when the pen-holder is applied to the front of the rack the preponderance of weight at the rear of the same will be overcome and the lid G will be closed.

As pen-holders vary in weight, it is advisable, in order to insure the proper action of the rack D, to furnish the latter with a variable counterbalance-weight. This I accomplish by providing one or both of the frames b of the rack (preferably of both, as shown) with an adjustable weight, m, the effect of which on the rack can be varied by moving it from or toward the center of the same. 70

The lid G of the ink-bottle has an elastic arm, n, which is hung to a pin, p, carried by lugs s on a clamp, J, the latter being adapted to embrace the neck of the bottle, and the arms of the same being elastic, so that lugs t, 75 at the outer ends of said arms, are caused to engage with the ribs or corrugations w, which are formed upon the neck of the bottle, the clamp being thereby retained in proper position, as twisting of the same on the bottle is 80 effectually prevented.

To protect the joint and prevent the access of ink thereto, I use a hood, x, which is adapted to fit over the lugs s, and is secured in place by the pivot-pin. An elastic hood, fitted to 85 the lugs after the pivot-pin has been applied, may be used in place of the hood shown; but the latter is preferred.

I have shown an inkstand having but one ink-bottle; but my invention may be used in 90 connection with stands having two or more bottles, if desired.

I claim as my invention—

1. The combination of the ink-bottle having a hinged lid, the pivoted pen-rack connected 95 to said lid, and having side frames, b b, and the weights n, adapted to and adjustable on the arms of said side frames, b, as set forth.

2. The combination of the bottle having a ribbed or corrugated neck with the clamp *J*, having elastic arms with lugs *t*, adapted to the said ribbed neck, as set forth.
- 5 3. The combination of the bottle, the collar *J*, with its lugs, the lid with its arm, and the hood *x*, as set forth.

In testimony whereof I have signed my name to this specification in the presence of two subscribing witnesses.

HENRY B. JONES.
